SEPARABLE SCISSOR CONSTRUCTION

Bogoa Strezoff, Minneapolis, Minn.

Application February 17, 1936, Serial No. 64,247

3 Claims. (Cl. 30—13)

My invention relates to scissor construction and particularly to scissors having one blade readily separable from the other.

Various types of scissors are in use, some having both blades of the ordinary straight-edged type and others having one blade of the straight-edged type associated with a second blade of special construction as, for example, in the case of hair thinning scissors used by barbers. In various trades and professions an individual may have use for a number of different types of scissors each of which includes one blade of the ordinary straight-edged type. In such cases it would be highly desirable to have scissors in which one blade is easily and quickly separable from the other so that one straight-edged blade may be operatively connected either to a second straight-edged blade or to any one of a plurality of special blades.

An object of my invention is to provide pivot joint construction for scissors and the like permitting quick and easy detachment of one blade of the scissors from the other to enable operative association of a first blade with any one of several second blades.

Another object is to provide scissors with separable pivot joint construction which is snugly fitting and yet free for easy pivoting when assembled in operative position.

A further object is to provide such pivot joint structure of simple, rugged and inexpensive construction.

These and other objects and advantages of the invention will more fully appear from the following description, made in connection with the accompanying drawing, wherein like reference characters refer to the same or similar parts throughout the various views, and in which:—

Fig. 1 is a view of a pair of scissors embodying my invention, the blades being shown in closed position in full lines and one blade being shown in dotted lines as it appears when swung relative to the other blade to a wide open position;

Fig. 2 is a view of another type of blade which may be substituted for one of the blades of Fig. 1;

Fig. 3 is a view, at enlarged scale and partially broken away, of the medial portion of the scissors of Fig. 1;

Fig. 4 is a sectional view taken along the line 4—4 of Fig. 3 as indicated by the arrows, and

Fig. 5 is the same as Fig. 4 except that it shows an alternative construction.

Referring to the drawing, and particularly to Fig. 1 thereof, my separably jointed scissors con-

sist, in general, of a pair of scissor members 5 and 6 comprising respective medial portions 5a and 6a, respective handles 5b and 6b and respective shearing blades 5c and 6c, the handle and blade of each scissor member extending in opposite directions from the medial portion thereof and the medial portions of the respective scissor members being connected together in crossed pivotal relation. All of the above described structure is in accordance with the conventional practice except the pivotal joint which I employ and which will be described.

The inner side of the medial portion 6a of the scissor member 6 carries a pivot stud 7 of non-circular cross section in inwardly projecting normal relation thereto. While other means could be used, the stud 7 is secured to the medial portion 6a of the scissor member 6 by means of a screw-threaded extension 7a thereof screw-threadedly retained in an internally screw-threaded apertured portion of the medial portion 6a as shown. The head 7b of the stud 7 is preferably of circular shape and may be slotted, as shown, if desired, to facilitate making of the above described screw-threaded connection. A jam-nut 7c is placed on the free end of the stud 7 as shown.

The stud 7 is of non-circular cross section as above mentioned, and, while various non-circular shapes could be used, I prefer to use a shape such as would be produced by taking a cylindrical stud and removing material to form a pair of diametrically oppositely located parallel flat faces such as the faces 7d. The stud 7 is secured to the medial portion 6a of the scissor member 6 with a line disposed diametrically thereof and parallel to the faces 7d displaced by an acute angle from the longitudinal axis of the scissor member 6 in a counter clockwise direction as viewed in Figs. 1 and 3. This acute angle is preferably in the neighborhood of 45 degrees. The line referred to above constitutes the longest diameter of the stud 7 and a diametrical line between the faces 7d constitutes the shortest diameter.

The medial portion 5a of the remaining scissor member 5 is provided with a centrally located circular aperture 8 therethrough for receiving the stud 7 in journaled relation thereto. The aperture 8 has a diameter exceeding the longest diameter of the stud 7 only sufficiently to permit the stud 7 to rotate in the aperture 8. Although the head 7b of the pivot stud 7 may be disposed so as to bear at its inner side against the outer side of the medial portion 5a of the scissor member 5, it is preferable that the outer end of the

- aperture 8 be increased in diameter to form a circular recess or depression 9 for receiving the head 7b at least to a portion of the depth of the head 7b as shown. The diameter of the recess 9 is such that the periphery of the head 7b will be encircled by the material defining the recess 9 closely but with clearance permitting free rotation of the head 7b in the recess 9 in journaled relation thereto.
- 10 Means is provided for permitting access to the aperture 8 and recess 9 for placing therewithin and removal therefrom of the stud 7 and its head 7b. To this end a notch or slot 10 is formed in the medial portion 5a of the scissor member 5 extending from an edge of the member 5 to the aperture 8 in radial relation to the aperture 8. Preferably, the slot 10 extends substantially laterally of the scissor member 5 toward the right as viewed in the full line portion of Fig. 1. The 15 width of the slot 10 is necessarily dimensionally intermediate the longest and shortest diameters of the pivot stud 7 and is preferably greater than the smallest diameter of the stud 7 only to an extent providing clearance permitting movement 20 of the stud 7 through the slot 10 laterally of the scissor member 5 when the faces 7d of the stud 7 are parallel to the sides of the slot 10. A groove 11, for accommodating the head 7b of the pivot stud 7, extends from the recess 9 to the edge of the medial portion 5a of the scissor member 5 in 25 co-directional relation to the slot 10. The width of the groove 11 is at least as great as the diameter of the stud head 7b and is preferably equal to the diameter of the head receiving recess 9.
- 30 A hair thinning scissor member 12 adapted for association with the scissor member 6 in substitution for the scissor member 5 is shown in Fig. 2. The scissor member 12 is identical with the scissor member 5 in its medial portion 12a and 35 the handle portion 12b and is provided with an aperture 8, recess 9, slot 10 and groove 11 identical with those described above in connection with the scissor member 5. The blade 12c is identical with the blade 5c of the scissor member 5 except 40 that the cutting edge thereof is notched and formed in accordance with the construction ordinarily found in hair thinning scissors of conventional design. Other similar scissor members having various types of cutting edges may be provided for association with the scissor member 6 if desired.
- 45 In normal use of my scissors the same are manipulated in the same manner as any scissors of conventional design. Within the range of 50 angles at which the respective scissor members 5 and 6 are disposed relative to each other in such use the stud 7 is always so disposed that the faces 7d are never parallel to the slot 10 and hence that the projected width of the stud 7 presented to the inner end of the slot 10 is always greater than the width of the slot 10 to prevent outward movement of the stud 7 through or into the slot 10. In this manner the scissor members 5 and 6 are positively retained in pivotal relation to each other in 55 normal use of the scissors. The journaled engagement of the circular head 7b of the pivot stud 7 with material defining the sides of the circular recess 9 assists in preventing lateral play 60 of the pivotal joint and its engagement with the material defining the bottom of the recess prevents separation of the scissor members 5 and 6 in the direction of the longitudinal axis of the stud 7.
- 65 When it is desired to separate the respective

scissor members 5 and 6 the same are spread apart to approximately their wide open position as represented in Fig. 1 by member 6 in full lines and member 5 in dotted lines. This is a position angularly displaced in the vicinity of 225 degrees from the fully closed position of the members 5 and 6. In the approximately wide open position described the faces 7d of the stud 7 are parallel to and aligned with the sides of the slot 10 so that the stud 7 may be slid through the slot 10 to disengage one of the members 5 and 6 from the other. The method of re-assembly is believed to be apparent and it should also be apparent that the member 12 of Fig. 2, or any other scissor member having similar construction 15 in its medial portion, may be substituted for the scissor member 5 in such re-assembly.

Another form of my separable pivot joint is illustrated in Fig. 5. In this form the non-circular pivot stud 10 is formed integrally with the 20 medial portion 6a of the scissor member 6. The pivot stud 10 and the medial portion 6a are apertured co-axially of the pivot stud 10, the lower portion of the material defining the aperture being internally screw-threaded and the upper portion being of slightly increased diameter. The pivot stud 10 is of the same cross-sectional shape and dimensions as the previously described pivot stud 7 and has flat faces 10a disposed at the same angle as the faces 7d of the pivot stud 7. A screw 11, having a head 11a of the same construction as the head 7b of the stud 7, is screw threadedly engaged in the above mentioned aperture with its head 11a disposed in the circular recess 9 of the scissor member 5. A jam nut 11b is placed on 30 the free end of the screw 11. The pivot stud 10 is, of course, normally journaled in the aperture 8 of the scissor member 5 and disengagement of the pivot stud 10 from the scissor member 5 is 35 accomplished in the same manner as employed 40 in disengaging the pivot stud 7 of the previously described embodiment of the invention. Adjustment of the scissors to compensate for wear is effected by suitably turning the screw 11. 45

With construction such as described above, it is obvious that scissors of various types and for various purposes may be readily available with much fewer parts than if a separate pair of non-separable scissors were provided for each purpose. If any scissor member of a set of scissor members such as mine becomes broken or damaged, it is not necessary to replace a complete pair of scissors since a new member may be readily assembled with an old member of complementary 55 construction. Also separation of the respective members of a pair of scissors such as mine greatly facilitates easy and accurate sharpening of the cutting edges thereof and where necessary, the cleansing and sterilizing thereof. 60

While my separable pivotal joint has been illustrated and described as applied to scissors, it should be obvious that such a joint is equally well adapted for use in any other tool or instrument having crossed, pivotally connected elements, such as, for example, many types of pliers, tongs, surgical and dental instruments, hand operated punches and stamps, cutters and tin-snips. 65

It is apparent that I have invented a novel, 70 useful, simple, rugged, inexpensive and easily manipulated type of separable pivotal joint adapted for use in tools and instruments having crossed pivotally connected members, and of construction permitting convenient and rapid 75

separation and re-assembly without the use of tools.

It will, of course, be understood that various changes may be made in the form, details, proportions and arrangement of the parts, without departing from the scope of my invention, which, generally stated, consists in a device capable of carrying out the objects above set forth and in the novel parts and combinations of parts disclosed and defined in the appended claims.

10 What is claimed is:—

1. A separable pair of scissors having in combination a pair of crossed, pivotally connected scissor elements having blade portions adapted to frictionally engage at their edges for shearing effect and a separable pivot joint connecting the medial portions of said elements and including a headed pivot stud projecting from the inner side of one of said elements and threaded into 15 said element for adjustable clamping action against said other scissor element, said stud having a non-circular portion adjacent its outer end having arcuate bearing surfaces concentric of its axis and having portions of less radius between 20 said bearing surfaces, said second scissor element being apertured to receive the cross sectional shape of said non-circular stud portion only when said scissor elements are disposed at an angle to each other outside the normal operating range 25 thereof and having a substantially circular bearing surface concentric with the axis of said stud for engaging the arcuate bearing areas of said stud after said scissor elements are joined and secured together.
- 30 2. A separable pair of scissors having in combination a pair of crossed, pivotally connected scissor elements having blade portions adapted to frictionally engage at their edges for shearing effect and a separable pivot joint connecting the medial portions of said elements and including a headed pivot stud projecting from the inner side of one of said elements and threaded into 35 said element for adjustable clamping action against said other scissor element, said stud having a non-circular portion adjacent its outer end having arcuate bearing surfaces concentric of its axis and having portions of less radius between 40 said bearing surfaces, said second scissor element having a circular aperture extending therethrough for normally retaining said stud in journalled relation thereto and a slot extending radially from said aperture to an edge of said second scissor element and having a width adapted to accommodate the portion of said stud between said arcuate bearing surfaces whereby said stud may be passed through said slot only when the maximum diameter of said stud is substantially parallel to said slot and means for retaining said stud against screw displacement relative to said first mentioned scissor element.

BOGOIA STREZOFF.

ing a non-circular portion adjacent its outer end having arcuate bearing surfaces concentric of its axis and having portions of less radius between said bearing surfaces, said second scissor element being apertured to receive the cross sectional shape of said non-circular stud portion only when said scissor elements are disposed at an angle to each other outside the normal operating range thereof and having a substantially circular bearing surface concentric with the axis of said stud 10 for engaging the arcuate bearing areas of said stud after said scissor elements are joined and secured together, and a jam nut threadedly engaging the projecting end of said pivot stud and engaging against said first mentioned scissor 15 element to retain said stud against screw displacement.

3. A separable pair of scissors having in combination a pair of crossed, pivotally connected scissor elements having blade portions adapted 20 to frictionally engage at their edges for shearing effect and a separable pivot joint connecting the medial portions of said elements and including a headed pivot stud projecting from the inner side of one of said elements and threaded 25 into said element for adjustable clamping action against said other scissor element, said stud having a non-circular portion adjacent its outer end having arcuate bearing surfaces concentric of its axis and having portions of less radius between 30 said bearing surfaces, said second scissor element having a circular aperture extending therethrough for normally retaining said stud in journalled relation thereto and a slot extending 35 radially from said aperture to an edge of said second scissor element and having a width adapted to accommodate the portion of said stud between said arcuate bearing surfaces whereby said stud may be passed through said slot only when the maximum diameter of said stud is substantially parallel to said slot and means for retaining said stud against screw displacement relative to said first mentioned scissor element.
